UNITED STATES PATENT OFFICE.

THOMAS M. FREEBLE, OF ROCHESTER, PENNSYLVANIA.

SAFETY APPARATUS FOR RAILWAYS.

1,171,333.

Specification of Letters Patent.

Patented Feb. 8, 1916.

Application filed April 12, 1911. Serial No. 620,681.

To all whom it may concern:

Be it known that I, THOMAS M. FREEBLE, of Rochester, Beaver county, State of Pennsylvania, have invented a new and useful improvement in Safety Apparatus for Railways, of which the following is a full, clear, and exact description, reference being had to the accompanying drawings, forming part of this specification, in which—

0. Figure 1 is a diagrammatic view illustrating one form of my invention and its application to a railway and its signal system; Fig. 2 is a detail view showing the brake valve and brake valve controlling magnet on a larger scale; Fig. 3 is a side view of one of the track contact sections; Fig. 4 is a sectional view of the same; Figs. 5 and 6 are views which are respectively similar to Figs. 3 and 4, but which show a modification; and Figs. 7 and 8 are diagrammatic views similar to Fig. 1, but showing further modifications of the invention.

My invention has relation to safety apparatus for railways, and is designed to provide apparatus which is especially adapted for use in connection with the ordinary block signal apparatus of the railway, for the purpose of insuring control of train movements in accordance with the block signal.

More specifically, my invention comprises means carried by the locomotive or other portion of the train for stopping or controlling the speed of the train, and means located along the trackway in suitable relation to the block signals and adapted for co-operation with the mechanism on the train and also controlled by the position of the block signals, whereby with a signal in the caution or danger position, the train will be automatically stopped or brought under control.

Referring first to that form of my invention shown in Fig. 1, the numeral 2 designates the track rails which are formed in insulated sections, the insulation being indicated at 3, and dividing the portion of the track shown into the blocks A, B, C, D and E. 4 designates batteries or other source of current, which are connected across the track rails of each block. 5 designates semaphores or other signals for respective blocks. 7 designates the track relays which control the signals 5 in a manner well known in block signaling, the signal system shown being of

that type in which the presence of a train in any block, short circuits a track relay or relays, and thereby sets the signal at danger. Each of the relays has two magnets, one of these magnets being connected across the track rails of the section which it protects, and the other magnet being connected across the track rails of the next succeeding section.

8 designates short contact sections, one of which is placed adjacent to the termination of each block and which may be located either between the track rails or adjacent thereto, so as to be engaged by a contact roller 9, or other device, which is carried by the locomotive or other part of the train. Each of the contact sections may be of the form shown in Figs. 3 and 4, having the overhanging top flange 10, with the under side of which the roller 9 makes contact, or they may be of the angle form shown in Figs. 5 and 6, in which the contact roller device 9 makes contact with the edge thereof, or they may be of any other suitable form. Each of the relay magnets 7 is provided with a pivoted armature 11, the two armatures being electrically connected in series with each other and forming part of an electric circuit, one terminal of which is connected to the adjacent contact section 8, and the other terminal of which is connected to one of the track rails of the block in which the contact section is located. This circuit includes a battery 12 or other source of supply.

13 is a magnet which is carried on a locomotive and which has one of its terminals connected by a conductor 13^a to a movable contact 14, which, in turn, is connected to or arranged to be actuated by the contact roller 9, before referred to. Any other contact device may be used instead of the roller 9. The other terminal of the magnet 13 is grounded through a conductor 13^b to the frame of the locomotive at 15.

16 is a battery or other source of current, having one terminal connected to the conductor 13^b and its other terminal ending in a contact point 17, which is normally engaged by the contact 14.

18 designates two movable contacts, one of which is connected to the conductor 13^a and the other of which is connected to the conductor leading from the battery 16 to the contact point 17. The two contacts 18 are arranged to be connected through a member 110

19 having an insulated portion 20, arranged to be moved by a centrifugal governor 21, which is driven by the train. When the speed of the train is above a certain predetermined maximum, the insulated portion 20 is moved between the contacts 18 to break the circuit between them, and when the speed of the train is below the maximum, the two contacts are connected through the 10 conducting portion of the member 19.

Each magnet 13 is arranged to operate an armature lever 22, which, in turn, actuates a speed-controlling device 23. This device may be a brake-applying valve or it may be 15 the throttle lever of an engine or the control lever of a motive driven vehicle. The magnet 13 is normally energized from the battery 16, and in this position, the speed-controlling device is in normal running position. The normal circuit of this magnet is from the battery 16 to and through the magnet and back to the battery through the contacts 14 and 17. One magnet 7 of each 20 of the track relays is connected in multiple with one of the magnets of the relay for the next succeeding block section.

The operation is as follows: Supposing a train equipped with the apparatus before described to be in the block B in the position indicated in Fig. 1. A train or other obstruction in block E, in the position indicated, will short circuit one of the magnets of each of the two adjacent track relays 7, thereby setting the semaphores 5 for the 30 track sections D and E at danger, and putting the semaphore 5 of the section C at caution, in the usual manner in block signaling. The short circuiting of the magnet 7 will drop the corresponding armatures 11, 40 as shown in Fig. 1. When the contact roller on the train block B engages the contact section 8 of the block C, if the speed of the train is at or below the predetermined maximum, the opening of the circuit at the contacts 14 and 17, which will be effected by the movement of the roller 9, will be without effect on the magnet 13, since the circuit for said magnet will be completed through the contacts 18 and governor-controlled member 19. If, however, the speed of the train exceeds the predetermined maximum for which the governor is set, the contacts 18 will be separated by the insulating portion 20 of the member 19, and the circuit of the magnet 13 will be opened, thereby actuating the speed-controlled device 23 either to stop the train or reduce its speed according to the character of said device. If, therefore, there is any obstruction in 50 the block E, the approaching train can not pass into block D without having its speed reduced or being brought to a stop. If there is no obstruction in the block E, the magnet 13 will not be affected, whatever 55 may be the speed of the train, since all the

relay magnets 7 will be in their normal energized condition, and the contact section 8 will be connected with its battery 12, so that as soon as the contact roller 9 engages said section, current will flow from the battery 12 through said section, and the roller 9, to and through the magnet 13, by way of the conductor 13^a. It will be apparent, therefore, that the speed-controlling device of the train will not be normally affected unless two conditions are presented: first, the proper signal or signals must be at danger; and second, the speed of the train must be above a predetermined maximum. With these two conditions existing, the train will be at once brought to stop or under control without any action on the part of the engineer.

While the invention is shown as applied to a block signal system in which two blocks 85 are simultaneously protected by danger signals and the third block by a caution signal, it will be obvious that it is equally adapted for use with block systems in which the only block protected by the danger signal is 90 that in which the train or obstruction which controls said signal is located. In other words, the contact section 8, which is made effective to control the speed of the train, in the manner described, may be placed at 95 any distance in advance of the danger point.

In the modification of my invention shown in Fig. 7, the speed device controlling magnet 24 is normally energized by a battery 25. Each locomotive carries two contact wheels 100 26 and 27. The locomotive also has a magnet 28, provided with an armature 29, adapted when the magnet is deenergized to engage a contact point 30, which is connected to one terminal of the magnet 105 24. The magnet 28 has one terminal connected to the frame of the locomotive at 31, and its other terminal connected to the contact wheel or roller 26. This terminal of the magnet 28 is also connected to the 110 terminal of the magnet 24 through the contacts 32^a and the governor-controlled contact 32. The arrangement of the track apparatus is substantially the same as in Fig. 1. This governor-controlled contact 32 has 115 an insulating portion 33 of insulating material. When the speed of the train is above a predetermined maximum, the contact 32 is moved by the governor so as to electrically connect the contacts 32^a, but when the speed of the train is below such maximum, the contacts 32^a are separated by the insulating portion 33.

When the contact rollers 26 and 27 engage any track section 8, there will be no 125 effect on the magnet 24, unless there is some obstruction in the controlling block section, and unless the speed of the train is above a predetermined maximum. If neither of these conditions exist (and the rollers 26 130

and 27 are on any track section), current will flow from the battery 12, through the contact section 8, to the roller 26, and through the magnet 28 and back to the frame of the locomotive at 31, thereby energizing the magnet 28 and holding up its armature contact 29. Even if the armature 11 should be dropped, the magnet 24 will still be unaffected, provided the speed 4 of the train is below the predetermined maximum, by reason of the governor-controlled contact 32 being in a position in which its insulating portion 33 will separate the contacts 32. If, however, the armature contact 11 has been dropped and the position of the governor-controlled contact 32 is such as to electrically connect the contacts 32 the magnet 28 remains deenergized, with its armature contact 29 dropped against the contact point 30 and thereby short circuiting the battery 25, through the contacts 32, the contact 26, the track section 8, contact 27, and contacts 29 and 30.

In the modification shown in Fig. 8, instead of employing short track contact sections, such as shown in the other figures, I employ in each block short insulated rail sections 34. In this form of my invention, one of the relay armatures 11^a is normally connected through contact 35 and conductor 36 with the short insulated section 34, and the other relay magnet armature 11^a is connected through the contact 37 and conductor 38 with the track rail adjacent to the short insulated section 34. The speed governor contacts 39 are arranged in parallel with the speed device controlling magnet 40, and the governor-actuated contact has a conducting portion 41 and an insulating portion 41^a, the latter being normally in position to separate the contacts 39. The locomotive carries the contact roller 42, which is connected to one terminal of the magnet 40, through its armature contacts 43. The other terminal of the magnet 40 is connected through battery 44, to the frame of the locomotive at 45.

It will be seen that the circuit of the magnet 40 is normally completed through the track rail, thereby maintaining the energization of said magnet. If the speed of the train is below the predetermined maximum, however, the circuit of the magnet 40 will be completed through the contacts 39 and 40. If the relay magnets 7 are energized, the passage of the contact roller 42 on to the insulated section 34 will have no effect upon the magnet 40, since its circuit is still completed through the conductor 38, contact 37, relay armature 11^a, contact 35 and conductor 36, these contacts and conductors bridging around the insulation at one end of the short section 34. If, however, one of the relay magnets 7 is deenergized by the presence of an obstruction in the controlling block, this bridge is opened and the circuit of the mag-

net 40 is also opened, unless the speed of the train is sufficiently low to maintain the circuit of the magnet through the contacts 39 and 41.

In order to prevent the locomotive from itself deenergizing an adjacent relay magnet when passing over one of the insulated track sections 34, the insulated joints 33 of the two track rails are placed in alternating relation.

All the forms of my invention comprise track contact members, circuits for energizing said members and controlled by the block signal system, a speed-controlling device on the train having a controlling magnet, a speed governor controlling in part the circuit of the magnet, and means whereby the said magnet may be energized or its circuit completed from a track contact member, provided the track is clear. If, however, an obstruction exists in the controlling block, the actuating magnet of the speed-controlling device is deenergized unless the speed of the train is sufficiently slow to prevent this.

My invention adds to the ordinary block system of a railroad simply the provision of the track contact sections 8 or 34, and the providing of the relay magnets 7 with another set of contacts. In the form shown in Figs. 1 and 7, a separate battery or other source of electricity is necessary for each track contact section, but this source is dispensed with in the arrangement shown in Fig. 8.

It will be seen that my invention is susceptible of various other embodiments in the details of arrangement of its circuits and of the speed-controlling apparatus carried by the train. It is also applicable to other types of block systems than the particular type illustrated and described.

My invention is applicable to electric railways as well as steam roads, and in using the terms "train", "locomotive", etc., I desire them to be understood as applying to any moving vehicle on a track.

I claim:

In safety apparatus for railways, the combination with track rails divided into separate block sections of two relay magnets for each block section, and connected directly across the track rails of that section to be controlled wholly by track conditions in that section, a track contact for each block section, said contact having a circuit connection with one of the track rails of that section, a source of current supply included in said connection, two electrically series connected movable contact members also included in said connection, said members being respectively controlled by the relay magnets of two other different block sections, a contact device carried by the train for engagement with the said track contacts, an electro-magnet, means for normally energizing said

4
magnet independently of the said track contacts, connections whereby said magnet may be energized through the track contacts, means controlled by the speed of the train for controlling said connections, and a train controlling device controlled by said magnet, substantially as described.

In testimony whereof, I have hereunto set my hand.

THOMAS M. FREEBLE.
